UNITED STATES PATENT OFFICE

RAYMOND V. PARSONS, OF CLEVELAND, OHIO, ASSIGNOR TO JOHNS-MANVILLE CORPORATION, OF NEW YORK, N. Y., A CORPORATION OF NEW YORK

INTERIOR FINISH CONSTRUCTION

Application filed November 5, 1927. Serial No. 231,276.

My invention relates to building construction; particularly to interior-finish construction, consists in a new and improved mode of applying and sustaining the plaster finish, as to walls and ceilings, and has for objects the protection of such finish from checking or cracking, such as usually occurs when the structural supports settle unevenly, and the provision of wall or ceiling finish which shall be effective both for heat and sound insulation.

By "plaster," as the term is herein used, any originally plastic material, capable of being laid while plastic and setting to solid and rigid consistency, is included. The high degree of inherent strength and stiffness of all the plastering materials used in building construction may not generally be appreciated. The structural adjuncts employed in association with plaster, e. g. lathing, of wood, wire-mesh, or expanded metal, are not so much needed as permanent reinforcements as for means of suspension in proper place, of the sheet of plaster, which when hardened by setting is amply strong, mechanically, to sustain not only itself but considerable loads.

In the majority of instances plaster is laid either directly upon a structural support, such as hollow tile or masonry, or upon a lathing rigidly secured to and thus forming part of the structural support itself. Almost, if not quite, without exception, such structural supports are subject to progressive alterations in position, as when the building settles, and such changes inevitably produce checks and cracks in the rigid sheets of attached plaster. Plaster laid upon such a support is subject to periodic changes by thermal expansion and contraction, and the inevitable differences between the plaster and the structural support, as measured by respective coefficients of expansion, tend to produce checks and cracks in the plaster.

My invention is diagrammatically illustrated in the drawings hereto annexed, in which Fig. 1 and Fig. 2 each shows in cross section a portion of a structural support, a plaster facing, and the intermediate stratum which is a salient feature; and is character-

ized by the employment of a stratum of material which as a whole is yielding distortable internally mobile, and is attached to the structural support at one side and to the plaster facing at the other. This stratum may be unitary or composite, its required physical characteristic is that it shall be capable of internal movement to a substantial extent in any direction parallel to its general surfaces without rupture and without detachment either from the structural support or the plaster facing, and inherently strong enough to serve as a suspensive support for the attached plaster. The latter characteristic enables it to hold the plaster facing in its proper relation to the structural support, the former enables it to absorb in its own yielding internally mobile and distortable body the settling or other movements of the structural support and the thermal expansions and contractions of the plaster and the structural support. The plaster facing is thus hung to its structural support, it floats, so to speak, on a yielding distortable and supple material between itself and the structural support.

The material which I have found best suited to the purpose, as a yielding medium of support, is wool felt or hair felt (preferably the latter) which has been self-quilted by the needling or puncturing process. This material has value as both a sound and heat insulator, possesses considerable mechanical strength, is reticular in structure and therefore lends itself to securement by adhesives, and to the attachment of plaster material which, when laid directly to the felt intrudes therein and, when set, is firmly anchored thereto. Referring to Fig. 1 of the drawings, A represents the structural support, B the stratum of yielding material, such as hair felt, in thickness one-half or three-quarters of an inch; C, a strong glue or cement, on which the felt is laid and which secures it adhesively and uniformly to the structural support; D the plaster facing, which, laid while plastic directly to the felt layer, intrudes into it, as indicated at E. The mechanical strength of the felt, its resistance to rupture under tension, is amply sufficient to sustain the weight of the plaster, even when the surface finished

therewith is a ceiling. When the plaster facing has set, its own inherent stiffness and strength come into service. Thereafter, any settling movements of the building structure are accommodated by the felt support on which the plaster facing hangs or floats, as are likewise expansion or contraction of the plaster finish, and the plaster itself is thus guarded against cracking or checking. The above described wall-finish has been tested as follows: A needled or punched hair felt layer, one-half inch thick was glued to a wooden board-surface, built without any diagonal bracing; to the felt layer a facing of plaster, one-half inch thick, was laid, and allowed to set. The wooden support was then racked to and fro, to produce changes of shape far greater than would result from even an extreme amount of settling in a building; these movements were wholly absorbed by the yielding of the felt layer, the rectangular plaster finish sheet remaining unaffected.

In Fig. 2, which represents in section an alternative form of interior construction, the structural support A', is of corrugated material, sheet-metal for instance; the yielding material layer B is secured to the support A' by a glue-layer C, and the plaster layer D, penetrating the open-textured yielding material at E, and conforming to the corrugated or undulating surface thereof, has its exposed surface finished flat, as usual.

By the mode of construction here illustrated, the plastic layer is molded with parallel ribs D', which afford structural stiffness in high degree to the plaster layer. As in the construction illustrated in Fig. 1 here also the yielding material B performs its function as a medium of securement and suspension for the plaster layer, and absorbs any distortions of the structural support A', thus preventing the transmission of stresses to the stiff plaster layer D.

I claim:

- 45 1. The combination of a structural support, a facing of plaster, and a connector of yielding distortable, internally mobile character between the structural support and the plaster facing.
- 50 2. The combination of a structural support, a stratum of yielding distortable, internally mobile material, and a facing of plaster, the plaster facing supported by the said stratum of yielding material and the latter in turn supported by the structural support.
- 55 3. The combination with a structural support, of a stratum of yielding distortable, internally mobile material and a facing of plaster, the said stratum of yielding material secured to the structural support at one surface and to the plaster at the other, sustaining the latter in its normal position with relation to the former.
- 65 4. The combination with a structural support, of a stratum of yielding distortable, in-

ternally mobile reticular material and a facing of plaster, the said stratum of yielding reticular material secured to the structural support at one surface and to the plaster at the other by intrusion of the plaster into said stratum, sustaining the latter in its normal position with relation to the former. 70

5. The combination with a structural support, of a stratum of yielding distortable, internally mobile reticular material and a facing of plaster, the said stratum of yielding reticular material adhesively secured to the structural support at one surface and to the plaster at the other by intrusion of the plaster into said stratum, sustaining the latter in its 75 normal position with relation to the former.

6. The combination with a structural support, of a stratum of felted distortable, internally mobile fibrous material and a facing of plaster, the said felted material secured to the structural support at one surface and to the plaster at the other, sustaining the latter 80 in its normal position with relation to the former. 85

Signed by me at New York, New York, this 90 second day of November, 1927.
